UNITED STATES PATENT OFFICE.

STUART L. CRAWFORD, OF ROCHESTER, NEW YORK.

DESIGN FOR A COMBINATION TUBE CONTAINER FOR FRUIT SYRUP, FLAVORING EXTRACTS, AND FRUIT ACIDS.

57,588.

Specification for Design.

Patented Apr. 26, 1921.

Application filed October 20, 1919. Serial No. 332,090. Term of patent 7 years.

To all whom it may concern:

Be it known that STUART L. CRAWFORD, citizen of the United States, residing at Rochester, in the county of Monroe and State of New York, has invented a new, original, and ornamental Design for a Combination Tube Container for Fruit Syrup, Flavoring Extracts, and Fruit Acids, of which the following is a specification, reference being had to the accompanying drawing, forming part thereof.

The figure is a perspective view of the design for a combination tube container for fruit syrup, flavoring extracts and fruit acids, showing my new design.

This tube is designed with two compartments, one at each end thereof, for the purpose of storing a flavoring extract in one of the compartments and fruit acid and coloring matter in the other of said compartments.

I claim:

The ornamental design for a combination tube container for fruit syrup, flavoring extracts, and fruit acids, as shown.

In testimony whereof I affix my signature.

STUART L. CRAWFORD.
